UNITED STATES PATENT OFFICE.

JOSEPH DANKS DAVIES, OF NATCHEZ, MISSISSIPPI.

STEAM PUMPING-ENGINE.

SPECIFICATION forming part of Letters Patent No. 340,984, dated May 4, 1886.

Application filed June 30, 1885. Serial No. 170,968. (Model.)

To all whom it may concern:

Be it known that I, JOSEPH DANKS DAVIES, of Natchez, in the county of Adams and State of Mississippi, have invented certain new and useful Improvements in Steam Pumping-Engines; and I do hereby declare the following to be a full, clear, and exact description of the invention, such as will enable others skilled in the art to which it appertains to make and use the same.

My invention relates to an improvement in steam pumping-engines.

In Patent No. 307,443, granted me November 4, 1884, a duplex pumping-engine was shown and described in which a connection uniting the piston-rods of two reciprocating engines served to render their movements relatively to each other positive, and to determine the length of stroke. Improved mechanism was also there shown for controlling the movement of the valves.

The object of my present invention is to provide mechanism, in connection with a duplex pumping-engine, whereby it may obtain greater degrees of expansion and uniformity of force; to provide suitable valves and valve mechanism for working expansively; to provide means for keeping the steam-cylinders hot; to provide connections between the beams to suit any location of the engines, and to provide auxiliary devices for opening and closing the valves of the pumps when pumping liquids.

With these ends in view my invention consists in certain features of construction and combinations of parts, as will be hereinafter described, and pointed out in the claims.

In the accompanying drawings, Figure 1 is a view of a duplex pumping-engine in side elevation, partly in section. Fig. 2 is a similar view of the engine with the auxiliary cut-off valves and casings removed. Fig. 3 is a view of one of the engines in horizontal section. Fig. 4 is a transverse section through the centers of the pumps. Figs. 5, 6, 7, 8, 9, and 10 are detached views of parts, and Figs. 11, 12, and 13 are different forms of connections to suit different locations.

For convenience in describing their construction and operation, the engines which are connected to form the duplex engine will be denominated "No. 1" and "No. 2."

a is the piston-rod of No. 1, and *a'* the piston-rod of No. 2.

b b' c c' are the beams and vibrating arms of the engines Nos. 1 and 2, respectively. 55

B and *B'* represent the pump-cylinders connected with the engines Nos. 1 and 2, and *b²* is a pin pivotally connecting the adjacent ends of the beams *b b'*.

The parts of the duplex engine as thus far mentioned are quite similar in construction and operation to those shown and described in the patent above referred to, and a minute description is dispensed with here.

c² is a crank-arm rigidly secured to the end 65 of the journal of the vibrating arm *c*, and *c²* is a double-crank arm rigidly secured to the journal *c³* of the vibrating arm *c'*. The wrist *e* lies opposite the wrist *d'* and moves in a contrary direction.

The wrists *d* and *d'* on the crank-arms *c²* and *c²* are connected by a link, *F*, provided with a slotted end or loop adapted to embrace the wrist *d'* and allow it to play therein in the direction of the length of the link. The wrists 75 *e* and *d* are connected by a link, *g*, pivotally secured on the wrist *e*, and adapted to embrace the wrist *d* and allow the same a play in the direction of its length. Rods *u* and *T* are pivotally secured to the link *F* and connect 80 the same with the levers *i* and *H'*, respectively. The lever *i* is pivotally secured on a support, *K'*, and has its opposite end connected to the valve-rod *n'*, which operates the auxiliary cut-off valve *m'* of the engine No. 2. 85

The lever *H'* is also pivoted on the support *K'*, and has the valve-rod *P'* connected with its opposite end, which valve-rod operates the main cut-off valve *o'* of the engine No. 2. The rod *A'* is also connected with the lever 90 *H'* at a point nearer the fulcrum *K'* than the connection of the rod *P'* therewith, and operates the valve *m³* of the auxiliary cylinder *m³*. Rods *u* and *T* connect the link *g* with the ends of levers *i* and *H*, fulcrumed on a support, *K*, 95 and connected with the valve-rods *n* and *P* of the auxiliary and main cut-off valves *m* and *o* of engine No. 1, in the same manner as the corresponding parts just described in connection with engine No. 2. A rod, *A*, is also 100 connected to lever *H* at a point nearer its fulcrum *K* than the connection of the valve-rod

P therewith, and operates the valve n^2 of the auxiliary cylinder m^2 .

The auxiliary cut-off valves m m' are preferably of the piston type and work in cylinders R R' , open at both ends to the auxiliary steam-chests s s' , and each communicating with the main steam-chests S S' through a single port, as r^4 r^2 . The main cut-off valves o o' are preferably slide-valves, and may have any desired lap. The valves n^2 m^5 in the auxiliary cylinders m^2 m^3 are also slide-valves, and are made short, so that they will not cover both steam-ports m^4 m^6 at the same time, but lap should be provided on the exhaust side.

15 The piston in the cylinder m^2 is connected with a piston or plunger— a^2 , for example—which works in a cylinder communicating with the cylinder B of the pump operated by engine No. 1. The piston of the cylinder m^3 20 is connected with a piston or plunger— a^3 , for example—which works in a cylinder communicating with the cylinder B' of the pump operated by engine No. 2.

x^2 is an equalizing-cylinder located at right angles to the axis of the engines and opposite the pin b^2 , connecting the adjacent ends of the beams b b' .

The piston-rod of the piston w is secured to a cross-head, v , connecting a pair of rods, 30 v , pivotally secured on the pin b^2 . The rods v are each provided with an elongated loop, v^2 , which embraces the journal of the vibrating arm e and admits of the travel required of the pin b^2 .

35 The equalizing-cylinder x^2 is provided with two inlet-valves, y , and two outlet-valves, y' . It is also provided with large clearance on each side of the piston w . Steam is admitted to the cylinder x^2 by a supply-pipe, x , to which 40 may be attached any of the well-known pressure-regulators. A pipe, Y , leads from the delivery-valves y' of the equalizer to the steam-jackets q of the engines. Said pipe Y is provided with a stop-cock, z , to throw the equalizer out of communication with the jackets whenever it is desired.

The auxiliary steam-chests s s' and the steam-chests of the auxiliary cylinders m^2 m^3 are connected with the boiler in any approved manner, as is usual in steam-engines. The steam-jackets are provided with a safety-valve, (not shown,) to limit the pressure of steam therein and allow the water of condensation to be returned to the boilers.

55 The operation is as follows: The piston of engine No. 1 is at the end of its stroke, moving in the direction of the arrow. The piston of No. 2 is at mid-stroke, moving in the direction of the arrow. The cut-off valve m is 60 opening its port and the main valve o opening its port s^2 . The valve m' has closed its port r^2 , while S^5 is still open. The piston No. 2 is now forced forwardly by the expansive force of the steam in the cylinder and in chest S' , 65 and as soon as it passes mid-stroke is assisted by the piston of No. 1 through the beams b b' . d and d' , now moving in the same direc-

tion, carry the rods u T forward, closing the port s^5 and moving the valves m' o' over their seats sufficiently to open the ports r^2 and s^7 by 70 the time the piston of No. 2 has finished its stroke; but the wrist e has been going in a contrary direction to d , and when the piston of No. 2 was leaving the mid-stroke position d the wrist e was moving faster than d , thereby opening the ports r^4 s^2 by means of the rods u T and the levers i H , admitting full steam to the piston of engine No. 1. As the piston of No. 2 moves forward on the last half of its stroke the wrist d of No. 1 carries its end of the link g forward, changing the direction of the rod T , and thereby closing the port r^4 before the piston of No. 1 reaches its mid-stroke, and leaving the steam in the chest S to act expansively in completing the stroke of No. 1. When the piston of engine No. 2 has completed its stroke and is starting on its return, it causes the wrist e to move in the same direction as the wrist d , and thereby, through the rod u 80 and lever i , rod T , and lever H , closes the ports r^4 s^2 and moves the valves m and o over their seats sufficiently to open the ports r^4 and s^7 by 85 the time or just before the piston of No. 1 has completed its stroke, and opening the port s^2 to the exhaust s^3 . The piston of No. 2, being under full pressure, will, during its first half-stroke, assist the piston of engine No. 1, through the connecting-beams b b' , to complete its stroke. Before the piston of No. 1 has completed its forward stroke the wrist d' has 90 carried its end of link F , with the return movement of the piston of No. 2, sufficiently far to close the port r^2 of the auxiliary cut-off valve m' before the piston of No. 2 reaches its mid-stroke, and the steam in cylinder of No. 2 and chest S' is left to operate expansively. As the piston of engine No. 2 is leaving its mid-stroke position on its return under full pressure of steam and assists No. 2 to complete its return stroke. During the first half of the return-stroke of the engine No. 1 the wrists d d' move in the same direction and close the port s^7 and open the port s^5 to the 100 exhaust s^6 , ready for the second forward stroke of the piston of the engine No. 2. As the engines continue to move the action of the valves will be repeated, as explained above. The valves n^2 m^5 have the same movement as 105 the valves o o' ; but as they have no lap, but clearance on the steam side, their action precedes the action of the valves o o' , and before the piston of engine No. 2 arrives at the end of its stroke an equilibrium of pressure is established in both ends of the cylinder m^3 , the 110 pressure of the liquid in the chamber a^3 driving the plunger in the cylinder a^3 back and allowing the discharge-valves o^3 to close. Just before the pump-piston a^5 of No. 2 starts on its return-stroke the valve m^5 closes the port m^4 and opens that end of the cylinder m^3 to the exhaust, thereby causing the plunger in the cylinder a^3 to complete its stroke and 115 120 125 130 135

open the discharge-valves o^2 , ready for the return of the pump-piston a^6 , thus preventing the jar which commonly accompanies the sudden changes in the motions of the pump-pistons. In a like manner the auxiliary engine m^2 serves to prevent jar in the pump operated by engine No. 1. Steam being admitted at any suitable pressure through the valves y of the equalizer x^2 , as the piston of engine No. 1 moves forward on its stroke, the valve z being closed, the confined steam in the end x of the equalizer x^2 presses on the piston w , and through its connection with the pin b^2 assists both engines; but when the piston w reaches its mid-stroke the pressure of steam in both ends $x x'$ of the cylinder x^2 is in equilibrium. On passing this point the steam in the end x' is compressed and the piston w offers resistance to the engines. On its return-stroke the piston w first offers assistance and then resistance, as before. It will be noticed that the piston w always starts on its stroke simultaneously with the beginning of the stroke of each engine. It therefore assists the engines at the beginning of their strokes, but passes into resistance before they reach their mid-strokes. It assists them again as they pass their mid-strokes, and offers resistance against them as they complete their strokes. A further use of this equalizer is to pump steam into the steam jacket or jackets q of the steam-cylinders, cylinder-heads, and receivers when used. To accomplish this the cock z is opened, and as the piston w is reciprocated in the cylinder x^2 steam will be forced through the valves y' into the jackets, while a portion of the steam will remain and effect the necessary equalization, as before explained. The steam driven into the jackets raises the temperature and the pressure of the steam already therein, thereby keeping the cylinders hot and preventing condensation from the walls of the cylinders and heads, cooling the entering steam within the cylinders.

45 The beams $b b'$ may be constructed as shown in Figs. 1, 2, and 3, or in any other desired form, and the journals connected to the piston-rods $a a'$ and to the arms $c c'$ may be formed integral with the rods and arms, or with the beams, or made separately from each or either, as found most convenient. So, also, the journals which support the arms $c c'$ may be integral therewith, or may be set stationary in the supporting-frame, and the arms be arranged

55 to swing thereon. In the latter case the crank-arms c and c' can be driven by any desired connection from arms c and c' , respectively.

If it is desired to use a very late cut-off, the rods $u u'$ may be detached, the valves m and m' pushed to leave the ports r^1 and r^2 open, and the engines be run by the main valves o and o' , which may be constructed by means of lap to cut off and cushion.

The engines are shown as resting one above the other; but it is evident that they may be on the same horizontal plane, or on end, or in any other desired position.

The auxiliary cylinders a^2 and a^3 are shown located between the pump-cylinders; but they may be placed in any convenient position, and the engines, which are described as single-cylinder engines, will work equally as well in the form of compound engines, either by placing the low-pressure cylinders endwise to the high-pressure cylinders, or by compounding from one to the other, using a receiver, as is customary in compound engines connected at right angles.

When it is desired to connect engines at some distance apart, the beams may be connected by a rod, v , for example, and the equalizer-cylinder x^2 be located between the ends of the beams, as shown in Fig. 11.

If it be desired to have the beams $b b'$ on the outside of the engines, they can be connected by a rod, v , Fig. 12, capable of sustaining in extension the strain imposed by the engines, and said rod may be provided with a piston and work in an equalizer-cylinder or not.

Fig. 13 shows a form of construction for the beams when it is desired to couple engines at different alignments to each other. In this form of connection the rod v , connecting the ends of the beams $b b'$, is in two sections, and the equalizing-cylinder x^2 is also in two sections, being connected by pipes, as shown, and filled with liquid.

The engines as above explained are adapted to pump air as well as liquids.

Instead of the double-acting equalizer shown and described, two single-acting equalizers may be employed, and a separate steam-pump driven from the ends of the beams $b b'$, or from any point in the connection between the ends of said beams, will answer in the place of the equalizer.

It is evident that numerous other modifications might be resorted to in the construction and arrangements of the several parts described without departing from the spirit and scope of my invention; hence I do not wish to limit myself strictly to the construction herein set forth; but,

Having fully described my invention, what I claim as new, and desire to secure by Letters Patent, is—

1. The combination, with two engines, of an equalizer and arms and links connecting the engines and equalizer, the parts being constructed and arranged whereby the equalizer assists the engines at the beginnings of their first and second half-strokes and resists them just before completing their first and second half-strokes, substantially as set forth.

2. The combination, with a steam-engine provided with steam-jackets, of an equalizer adapted to regulate the motions of the engines and pump steam into the jackets, substantially as set forth.

3. The combination, with a steam-engine provided with jackets, and an equalizing-cylinder provided with a piston operated by the pistons of the engine, of check-valves located in the pipes communicating with each end of

the equalizing-cylinder and the pipe leading to the jackets, and in the pipes communicating with each end of the equalizing-cylinder and the steam-supply pipe, substantially as set forth.

4. The combination, with an equalizer adapted to regulate the motions of the engines and supply steam to the steam-jackets, of a stop-cock adapted to shut off the equalizing-cylinder from the jackets, substantially as set forth.

5. The combination, with two connected engines and their main and cut-off valves, of the valve-operating mechanism, consisting of the links, the crank-arms on which the links are mounted, the lever connected with the valve-rods, and the rods connecting the said levers with the links, substantially as set forth.

6. The combination, with a pumping-engine, of one or more auxiliary engines connected to auxiliary pump-pistons, the parts being arranged, substantially as described, to cause the pump-valves to open and close by the change of water-pressure in the pumps, caused by the auxiliary engine or engines,

without preventing the pump-piston from finishing its stroke, substantially as described.

7. The combination, with two engines and a pair of vibrating beams connected with the piston-rods of the engines and with each other, of a rod joining the beam-connection and a piston working in an equalizing-cylinder, substantially as set forth.

8. The combination, with a pair of engines having one or more equalizers, of beams connected at one end to the piston-rods and at the other end to each other in such a manner as to enable the equalizer or equalizers to assist in regulating the motion of the engines or pump steam into the jackets, or both, and vibrating arms operated by the beams, substantially as set forth.

In testimony whereof I have signed this specification in the presence of two subscribing witnesses.

JOSEPH DANKS DAVIES.
